US0D1073125S

(12) **United States Design Patent** (10) **Patent No.:** **US D1,073,125 S**
(45) **Date of Patent:** **** Apr. 29, 2025**

(54) **ACCESS CONTROL GATE**

(71) Applicant: **Magnetic Autocontrol GmbH**,
Schopfheim (DE)

(72) Inventor: **Timo Rauer**, Rheinfelden (DE)

(73) Assignee: **Magnetic Autocontrol GmbH**,
Schopfheim (DE)

(**) Term: **15 Years**

(21) Appl. No.: **29/822,003**

(22) Filed: **Jan. 5, 2022**

Related U.S. Application Data

(62) Division of application No. 35/510,369, filed on Jul. 29, 2019 (U.S. filing date under 35 U.S.C. 384), and having an international filing date of Jul. 29, 2019, now abandoned.

(57) **CLAIM**

The ornamental design for an access control gate as shown and described.

DESCRIPTION

FIG. 1 is a top view of an access control gate showing my new design in a first configuration;

FIG. 2 is a top view thereof in a second configuration;

FIG. 3 is a top view thereof in a third configuration;

FIG. 4 is a left end view of the access control gate of FIG. 3;

FIG. 5 is a left end view of the access control gate of FIG. 1; and,

FIG. 6 is a left end view of the access control gate of FIG. 2.

The broken lines indicate environment and portions of the access control gate and form no part of the claimed design.

1 Claim, 6 Drawing Sheets
